UNITED STATES PATENT OFFICE.

WILLIAM M. CAVANAUGH, OF NEW YORK, N. Y.

CHAIR SEAT.

Application filed October 18, 1923. Serial No. 669,226.

To all whom it may concern:

Be it known that I, WILLIAM M. CAVANAUGH, a citizen of the United States, and a resident of the borough of Richmond, Richmond County, State of New York, have invented certain new and useful Improvements in Chair Seats, of which the following is a specification.

My invention relates to an improvement 10 in seats for chairs, and particularly to leather seats, one of the objects of the invention being the provision of a chair seat in which flexing and bending of the leather in the manufacture and application of the seat 15 have been eliminated.

A further object of the invention is the provision of a unitary leather chair seat structure which is adapted to be applied to a chair with ease and facility.

20 A still further object of my invention is the provision of a chair seat of leather in which a nailing or securing strip is provided which is adapted to be secured directly to the chair, this strip being independently attached as by sewing for example to the main portion or body of the chair seat, means also being provided whereby the tacks or other devices employed for holding the seat in place are concealed.

30 A further object of the invention is the provision of reinforcing material adapted to be attached to the leather of the seat and to take some of the strain when the seat is in use.

35 I am aware that chair seats have heretofore been constructed of leather but the usual practice is to apply a comparatively thin piece of leather to a wooden frame, the leather being turned down around the edges 40 of the frame and secured to the frame in any convenient manner. Such an arrangement, however, is not satisfactory for several reasons. In the first place turning the leather down around the edges of the frame causes 45 the leather to very soon wear through or to crack, while in the second place the leather, in order that it may be folded or turned down around the edges of the frame, must be so thin that it soon wears out.

50 In my arrangement, a very heavy leather may be employed, sole leather being preferred and no turning of the leather down around the edge of a frame is necessary at all. In fact in my improved structure the seat is a unitary affair and no extra frames or other appurtenances are necessary at all.

In the accompanying drawings—

Figure 1 illustrates my improved chair seat applied to a chair, part of the seat being broken away to illustrate its construction;

Fig. 2 is a bottom plan view of the seat of Fig. 1; and

Figs. 3 and 4 are similar views of modified constructions.

Referring to Figs. 1 and 2, 1 designates a chair to which my improved chair seat may be applied. The chair is provided with the usual seat opening 2 cut away as indicated to provide a ledge 3 on which the chair seat is 60 to rest and by which it is to be supported.

The chair seat comprises a piece of leather, preferably a good grade of sole leather, designated 4 cut to conform in shape to the opening 2 but small enough so that when in 70 position an annular space designated 5 will be left all around the seat between the top or body of the seat and the chair.

75 Sewn or otherwise attached to the under side of the body portion 4 is a comparatively narrow strip 6, wide enough to not only rest upon the ledge 3, but projects some distance beyond the edge of the ledge so as to extend some distance beyond the edge of the body portion of the seat. This strip may be made 80 in sections if desired and provides a flange all around the edge of the body 4. Interposed between the body portion 4 and the securing strip or strips 6 is a reinforcing strip or layer 7 of canvas, wire mesh or other suitable material this reinforcing material being 85 preferably cemented to the body portion 4 throughout its entire surface.

90 The seat is secured in position by nailing, for example, through the securing strip or strips 6 after which a sectional filler strip is cemented or otherwise secured in the spaces 5 between the edges of the body portion 4 and the frame of the chair, this strip lying flush with the upper surface of the 95 body 4.

100 It will be seen that this construction provides a very neat and compact structure with the means for securing the seat in place entirely hidden, the usual bending of the leather about a frame, in fact the usual frame, being dispensed with entirely.

105 My improved structure also provides a comfortable all leather seat which will last almost indefinitely owing to the fact that the 110 same can be constructed of heavy sole leather if desired, the reinforcing material

or strip 7 preventing permanent sag or depression of the body portion 4 so that the neat appearance of the seat is indefinitely preserved.

5 In the modified form of construction illustrated in Fig. 3 I have provided a chair seat similar to that already described, the canvas or fabric reinforcing strip 7 of Fig. 1 having been replaced by interlaced thin metal strips 9, and narrow strips 9' of fabric or webbing while in Fig. 4 I have used a woven cane reinforcing structure designated 10.

Having particularly described my invention 15 in what I claim and desire to secure by Letters Patent is:

1. A chair seat comprising a flat leather body portion, a flat leather securing strip secured to the under side of the body portion and extending beyond the edges thereof

to provide an annular flange about the periphery of the body portion, and a concealing strip overlying said flange and lying flush with the top surface of the body portion.

2. A chair seat comprising a leather body portion, a securing strip secured to the under side of the body portion and extending beyond the edge thereof to provide an annular flange extending around the edge of the body portion, reinforcing material interposed between the securing strip and the body portion of the seat and secured to both of them, and a concealing strip overlying said flange and lying flush with the top surface of the body portion.

This specification signed this 15th day of October, 1923.

WILLIAM M. CAVANAUGH.
